UNITED STATES PATENT OFFICE.

JAMES PHIPPS, OF PHILADELPHIA, PENNSYLVANIA, ASSIGNOR TO MARTIN LANDENBERGER & COMPANY, OF SAME PLACE.

DESIGN FOR TRIMMING.

Specification forming part of Design No. **6,638**, dated May 6, 1873; application filed April 15, 1873.

B.

To all whom it may concern:

Be it known that I, JAMES PHIPPS, of Philadelphia, Pennsylvania, have invented a Design for a Fringe or Border, of which the following is a specification:

The figure in the accompanying drawing clearly illustrates my design for a fringe or border, which has scalloped edges *a a* formed of a single thread or series of threads crossing the band *b* or body of the fringe, first in one direction and then in the other, so as to form a series of loops or scallops, and being itself partially covered and crossed upon the

said body *b* by a zigzag thread, *d*, tied down at the angles, as shown.

Irrespective of the colors employed, I claim—

The design for a fringe or border, substantially as described, and as represented in and by the accompanying drawing.

In testimony whereof I have signed my name to this specification in the presence of two subscribing witnesses.

JAMES PHIPPS.

Witnesses:

ROBERT McCONNELL,
JOHN F. TAGUE.
